UNITED STATES PATENT OFFICE.

STUART R. STONE, OF NEW YORK, N. Y.

RELAY.

1,083,566.

Specification of Letters Patent.

Patented Jan. 6, 1914.

Application filed August 11, 1911. Serial No. 643,494.

To all whom it may concern:

Be it known that I, STUART R. STONE, a citizen of the United States, and a resident of the city of New York, borough of Brooklyn, in the county of Kings and State of New York, have invented a new and Improved Relay, of which the following is a full, clear, and exact description.

My invention relates to relays for general use, and more particularly to a type of relay especially suitable for use in connection with fire alarm systems, annunciators and the like, where the purpose of the relay, directly or indirectly, as the case may be, is to control one or more alarms.

More particularly stated, my invention comprehends a relay provided with a double-ended magnet; that is, a magnet having two poles or sets of poles extending in opposite directions and operating to some extent independently of each other.

My invention further comprehends a relay provided with armatures of different kinds, controllable selectively by different degrees of strength in the currents employed for energizing the relay magnet.

Reference is to be had to the accompanying drawings forming a part of this specification, in which similar characters of reference indicate corresponding parts in both views.

Figure 1 is a diagram showing my improved relay as employed for controlling a number of separate devices, including alarms of different kinds, and also controlling movements of a drop shutter, the movable parts occupying their respective normal positions, and Fig. 2 is a diagram somewhat similar to Fig. 1, but showing the movable parts as occupying their respective abnormal positions.

A magnet 3 is provided with an armature lever 4, which is mounted upon a pivot 5 and adapted to swing in a vertical plane. A retracting spring 6 is connected with this armature lever for the purpose of normally keeping it raised, according to Fig. 1. The armature lever 4 carries an insulating member 8 and also a hook 7, this hook being, by virtue of the member 8, insulated from the armature lever. Below the armature lever

is a contact button 9. A shutter hook is shown at 10 and is mounted to swing upon a pivot 11. A drop 12 is mounted upon a pivot 13 and is adapted to swing to the right, according to Figs. 1 and 2, whenever released by the shutter hook 10.

The magnet 3 is provided with poles 14, 15, extending in opposite directions. Adjacent to the pole 15 is an armature lever 16, which is mounted to swing upon a pivot 17. Disposed below the armature lever 16 is a contact button 18, which is adapted to be engaged by this armature lever when the latter is dropped, as hereinafter explained.

The parts above described constitute practically the mechanism of the relay, but various auxiliary devices of the kind shown may be employed in connection with the relay. In this instance I show a fusible grid 19, a resistance coil 20 and a circuit-closing key 21, which are connected with the relay and with a battery 22. A wire 23 extends from the battery 22 to the magnet 3. A wire 24 is connected with the armature lever 16. A wire 25 leads from the contact button 18 to an instrument 26, which may be either a bell, a lamp or a relay, as desired. From this instrument a wire 27 leads to a wire 28, the latter being in communication with the contact button 9. A wire 29 is connected with the wires 27 and 28 and also with a wire 30, the wire last mentioned leading to the battery 22. A wire 31 is connected with the wires 29 and 30 and with the contact button 21^a of the key 21. A wire 32 is connected with the battery 22 and with the wire 23. A wire 33 is connected with the key 21 and with a wire 34, the latter leading to the fusible grid 19. From this fusible grid a wire 35 leads to the resistance coil 20. A wire 36 is connected with the latter and also with the wire 31 and the contact button 21^a. A wire 37 is connected with the magnet 3 and with the wire 24. A wire 38 is connected with the wires 24 and 37 and also with the wires 33 and 34. A wire 39 is connected with the armature lever 4 and with a bell 40, the latter being also connected with the wire 32.

When the various movable parts occupy their respective normal positions, as indi-

cated in Fig. 1, a slight amount of current is always flowing through the following circuit: battery 22, wire 23, magnet 3, wires 37, 38, 34, fusible grid 19, wire 35, resistance 5 coil 20, wires 36, 31 and 30, back to battery 22. The armature lever 16 being unrestrained and easily affected, is thus maintained in its raised position, and hence out of engagement with the contact button 18, as 10 will be understood from Fig. 1. If, now, for any cause, the battery 22 becomes totally inert, the magnet 3 is thereby deenergized and consequently the armature lever 16 drops into its lowermost position; that is, 15 into engagement with the contact button 18. The following circuit is thus completed: battery 22, wire 23, magnet 3, wire 24, armature lever 16, contact button 18, wire 25, instrument 26, wires 27, 29 and 30, back to battery 22. This energizes the instrument 26, which may, as above indicated, serve the purpose of an alarm. This action takes place whenever the fusible grid 19 is destroyed by fire. Suppose now that the operator depresses the key 21. The following circuit is thus completed: battery 22, wire 23, magnet 3, wires 37, 38, 33, key 21, contact button 21^a and wires 31, 30 to battery 22. This circuit being one of low resistance, 25 causes the magnet 3 to be energized to a considerable extent. The result is that the armature lever 4 is drawn down into engagement with the contact button 9 and the shutter hook 10 is actuated and the drop 12 thereby released. The engagement of the armature lever 4 with the contact button 9 completes the following circuit: battery 22, wire 32, bell 40, wire 39, armature lever 4, contact button 9, wires 28, 29 and 30, back 30 to battery 22. This circuit may be used to energize any alarm, relay or instrument of any kind which may be inserted within it.

Referring to the circuits which are closed when either of the armatures 4 or 16 comes 45 into contact with the coöperating elements, the following is to be noted: The intensity of the current to retain the armature 16 in the position shown in Fig. 1 is small; in fact, the intensity of such current is substantially 50 less when the armature is in such position than when the armature 4 is brought into the position shown in Fig. 2. When the armature 16 drops, coming into engagement with the contact 18, a circuit through the magnets 3 is closed, the current which flows through these magnets, however, not returning such armature to the position shown in both figures due to the fact that this armature 16 has fallen out of the field of force 55 due to such current; of course, this relation of the armature 16 to the magnetic field due to the current circulating through the electro-magnet 3 is determined gravimetrically, the distance through which the armature

must fall before engaging the contact 18 being determined with respect to such field of force. 65

As will be understood from the foregoing description, the two armature levers 16 and 4 are of unequal degrees of sensitiveness, the 70 armature lever 16 being lifted with the expenditure of less electric energy than that necessary to pull down the armature lever 4. It will thus be seen that the relay as a whole exercises a selectivity as between currents 75 of different strength, a weak current shifting the position of the armature lever 16, while a much stronger current is required to shift the position of the armature lever 4. It will also be noted that the armature levers 80 4 and 16 are used for independent purposes, and that the armature lever 4 controls not only an electric circuit, but also a drop shutter, which is merely a form of visual signal, its control over this drop shutter being direct. It will also be noted that as there are two armatures mounted respectively at the two ends of the magnet, the attraction of one armature partially closes the magnetic circuit, but the magnetic circuit is not completely closed — that is — completely closed through metal until both armatures are attracted at the same time. 85

I do not limit myself to the precise arrangement of the parts here shown and described, for the reason that variations may be made therein, without departing from the spirit of my invention, the scope of which is commensurate with my claims. 90

Having thus described my invention, I 100 claim as new and desire to secure by Letters Patent:

1. In a relay, the combination of an electro-magnet having pole faces at its ends, an armature adapted to be influenced by the electro-magnet adjacent one pole face, and a second armature adjacent the other pole face, a source of electric current connected to said magnet, said second armature being adapted to be held adjacent the pole face 110 when said electro-magnet is energized and to assume a position beyond the range of the normal magnetic field of said magnet when the latter is deenergized, a contact with which the second armature engages on assuming such position, and a circuit including the magnet, said contact and said second armature. 115

2. In a relay, the combination of a plurality of electro-magnets placed side by side, each electro-magnet having pole faces at the ends, an armature adjacent one end of the electro-magnets and normally retracted, a second armature adjacent the other end of the electro-magnets and adapted to be held normally adjacent the pole faces when said electro-magnets are energized, and forming a magnetic path between said magnets, said 125

second armature being adapted to fall from the adjacent pole faces when the magnets are deenergized, a contact with which the said second armature engages after such fall, and a circuit including said magnets, said contact and said second armature.

In testimony whereof I have signed my

name to this specification in the presence of two subscribing witnesses.

STUART R. STONE.
